Application September 14, 1934, Serial No. 53,289

Term of patent 14 years

To all whom it may concern:

Be it known that we, Walter Czarnecki, and
Walter V. Czarnecki, Jr., citizens of the United
States, residing at Eddington, in the county of
Bucks, and Commonwealth of Pennsylvania, have
invented a new, original, and ornamental Design
for a Combined Valve and Strainer Housing, of
which the following is a specification, refer-
ence being had to the accompanying drawings
forming a part thereof.

Figure 1 is a view of the combined valve and
strainer housing in side elevation,

Figure 2 is a view of the combined valve and
strainer housing in top plan, and

Figure 3 is a view of the combined valve and
strainer housing in end elevation.

We claim:

The ornamental design for a combined valve
and strainer housing, as shown.

WALTER CZARNECKI.
